UNITED STATES PATENT OFFICE.

ANTHONY B. POOL AND JOSEPH J. BEALS, OF BOSTON, MASSACHUSETTS.

CAR-BRAKE.

SPECIFICATION forming part of Letters Patent No. 446,981, dated February 24, 1891.

Application filed June 26 1890. Serial No. 356,753. (No model.)

To all whom it may concern:

Be it known that we, ANTHONY B. POOL and JOSEPH J. BEALS, both of Boston, in the county of Suffolk, State of Massachusetts, 5 have invented certain new and useful Improvements in Car-Brakes, of which the following is a description sufficiently, full, clear, and exact to enable any person skilled in the art or science to which said invention appertains to make and use the same, reference being had to the accompanying drawings, forming part of this specification, in which—

Figure 1 is a sectional elevation showing the end of a street-car provided with our improvement, and Fig. 2 a side elevation of the same.

Like letters and figures of reference indicate corresponding parts in the different figures of the drawings.

20 Our invention relates to a brake mechanism for street-railway cars; and it consists in certain novel features hereinafter fully set forth and claimed, the object being to produce a simpler, cheaper, and more effective 25 device of this character than is now in ordinary use.

The nature and operation of the improvement will be readily understood by all conversant with such matters from the following 30 explanation.

In the drawings, A represents the body of the car, B the dasher, and C the truck considered as a whole, these parts being of the ordinary form and construction. A horizontally-arranged worm or endless screw D is fitted to rotate in brackets d, secured to the bottom of the car, the threads of said worm running from the center f to the ends in opposite directions. Two parallel horizontally-arranged rods g are secured in the brackets d, respectively, above and below the worm D. Two blocks h i are fitted to slide on said rods g, and are threaded to respectively travel on the worm-sections m p. The 45 brake-beams q r are pivoted to the car-body in the usual manner, and rods t v, respectively, connect the blocks h i with said beams. On the outer end of each of said rods an elliptic spring w is secured centrally, the ends 50 of said spring bearing against the brake-beams and cushioning the pull of said rods. From each end of the worm D a rod x leads

to the platform, the outer ends of said rod being mounted in a bracket y on the lower end of the dasher B. On the upper edge of 55 the dasher a small shaft z is mounted, which bears a sprocket-gear 15, which is connected by a chain 16 with a similar sprocket 17 on each rod x. A hand-wheel 18 is mounted on the shaft z.

In the use of our improvement, by turning said handle the worm D is rotated, causing the blocks h i to travel thereon and draw the beams q r inward, the shoes 20 on said beams being thus forced into engagement with the 65 car-wheels and braking the car in the ordinary manner. By rotating the handle in the opposite direction said blocks h i are moved outward on the worm, freeing the brake-shoes.

70 The springs w on the brake-beams permit a slight lost motion to the shoes and prevent too great a strain on the rods t v.

Having thus explained our invention, what we claim is—

75 1. In a car-brake, a right and left hand worm fitted to rotate on the car-body, mechanism for actuating said worm from the car-platform, blocks fitted to travel in opposite directions on said worm, rods respectively connecting said blocks with the brake-beams, and springs on the outer ends of said rods in engagement with said beams, substantially as described.

2. The combination of the car and truck 85 with the worm D, fitted to rotate in hangers on the car-body, the blocks h i, traveling on said worm, the rods t v, connecting said worm with the brake-beams, springs on the outer end of said rods in engagement with said 90 beams, and means, substantially as described, for rotating said worm.

3. The combination of the car with the worm D, fitted to rotate thereon, the block h i, traveling on said worm, the rods t v, connecting 95 said blocks with the brake-beam, and the sprockets 17, mounted on said worm and connected by chains with a handle-sprocket on the car-dasher, substantially as described.

ANTHONY B. POOL.
JOSEPH J. BEALS.
